ALKALI METAL SALTS OF CYCLOPENTADIENYL CARBOXYLIC ACID MANGANESE TRICARBONYL SALS AND THEIR FREE ACIDS

John Kozikowski, Walled Lake, Mich., and Michael Cais, Haifa, Israel, assignors to Ethyl Corporation, New York, N.Y., a corporation of Virginia
No Drawing. Original application Aug. 12, 1960, Ser. No. 49,135. Divided and this application May 13, 1963, Ser. No. 283,144

3 Claims. (Cl. 260—429)

This application is a division of application Ser. No. 49,135, filed Aug. 12, 1960, now abandoned.

This invention relates to a variety of organometallic compounds and the processes employed in their production. More specifically, this invention relates to compounds and processes involving the use of a cyclopentadienyl sulfonic acid manganese tricarbonyl compound.

An object of our invention is to provide new organometallic compounds and processes for their preparation. A further object is to provide cyclopentadienyl manganese tricarbonyl derivatives and processes for their preparation. Additional objects will become apparent from a reading of the specification and claims which follow.

The objects of this invention are accomplished by providing alkali metal salts of cyclopentadienylcarboxylic acid manganese tricarbonyls and the corresponding free acids obtained by acidifying said alkali metal salts. The alkali metal salts may be prepared from compounds having the formula:

These compounds are made, as in the case of the $\{[(\text{tricarbonylmanganese})\text{cyclopentadienyl}]\text{ carbonylmethylsulfonyl}\}$ cyclopentadienyl manganese tricarbonyl, from reaction of the alkali metal salt of a cyclopentadienyl sulfonic acid manganese tricarbonyl with an appropriate haloacylcyclopentadienyl manganese tricarbonyl compound. In the above formula, the group R is a univalent hydrocarbon group, the group R' is a divalent hydrocarbon group, and R'' is hydrogen or R, each hydrocarbon group containing from one to about eight carbon atoms, x is an integer ranging from zero to three, and y is either zero or one. The above compounds are reacted with a base such as sodium hydroxide and a hydroxyl-containing solvent such as water or an alcohol such as ethanol to form a $[(\text{hydrocarbysulfone})\text{ cyclopentadienyl}]\text{ manganese tricarbonyl}$ and the alkali metal salt of a cyclopentadienylcarboxylic acid manganese tricarbonyl. These compounds have the respective formulae:

2

and

II

In the latter Formula II, M is an alkali metal.

In Formulae I and II, R is a hydrocarbon group containing from one to about eight carbon atoms, x is an integer ranging from zero to three, and y is either zero or one.

The alkali metal salt of the cyclopentadienyl carboxylic acid manganese tricarbonyl is readily separated from the cyclopentadienyl sulfone manganese tricarbonyl compound by means of extraction. The alkali metal salt is then acidified to form the carboxylic acid compound which is insoluble in an aqueous medium and can be filtered off.

To further illustrate this embodiment of our invention, there is presented the following example.

Example I

Four grams of $\{[(\text{tricarbonylmanganese})\text{cyclopentadienyl}]\text{ carbonylmethylsulfonyl}\}$ cyclopentadienyl manganese tricarbonyl, two grams of potassium hydroxide, 50 ml. of ethanol and 20 ml. of water were refluxed for 15 hours, cooled and poured into 400 ml. of water. Crystalline plates separated out and were filtered to yield 1.5 grams of a solid which was identified as $[(\text{methylsulfonyl})\text{cyclopentadienyl}]\text{ manganese tricarbonyl}$.

The aqueous filtrate was acidified with hydrochloric acid and the solid which precipitated was filtered off. The solid precipitate was recrystallized from benzene to give 1.8 grams (93 percent yield) of cyclopentadienyl carboxylic acid manganese tricarbonyl as yellow needle-like crystals having a melting point of 194–195°C. The compound was identified by means of its infrared spectrum and analysis. Found: Mn, 22.1 percent. Calculated: Mn, 22.2 percent.

The preparation of $\{[(\text{tricarbonylmanganese})\text{cyclopentadienyl}]\text{ carbonylmethylsulfonyl}\}$ cyclopentadienyl manganese tricarbonyl, the alkali metal salt of a cyclopentadienyl sulfonic acid manganese tricarbonyl, haloacylcyclopentadienyl manganese tricarbonyl, and other related compounds is fully described in our copending application Ser. No. 283,139, filed May 13, 1965, now U.S. Patent No. 3,205,245, issued Sept. 7, 1965.

Among the important uses of our compounds is their use as fuel and oil additives. For example, they are useful antiknocks when added to gasoline. They may be used as primary antiknocks in which they are the major antiknock component in the fuel or as supplemental antiknocks. When used as supplemental antiknocks, they are present as the minor antiknock component in the fuel in addition to a primary antiknock such as a tetraalkyllead compound. Typical alkyllead compounds are tetraethyllead, tetrabutyllead, tetramethyllead and various mixed lead alkyls such as dimethyldiethyllead, diethyldiethyllead and the like. When used as either a supplemental or primary antiknock, our compounds may be present in the gasoline in combination with typical scavengers such as ethylene dichloride, ethylene dibromide, tricresylphosphate, trimethylphosphate and the like.

3

The compounds of our invention have further utility as additives to residual and distillate fuels generally, e.g., jet fuels, home heater fuels and diesel fuels, to reduce smoke and/or soot formation. Also, they may be employed as additives to lubricating oils in which case they act to improve the lubricity of the base oil.

Our compounds are further useful in many metal plating applications. In order to effect metal plating using the compounds, they are decomposed in an evacuated space containing the object to be plated. On decomposition, they lay down a film of metal on the object. The gaseous plating may be carried out in the presence of an inert gas so as to prevent oxidation of the plating metal or the object to be plated during the plating operations.

The gaseous plating technique described above finds wide application in forming coatings which are not only decorative but also protect the underlying substrate material.

Deposition of metal on a glass cloth illustrates the applied process. A glass cloth band weighing one gram is dried for one hour in an oven at 150° C. It is then placed in a tube which is devoid of air and there is added to the tube 0.5 gram of [(methylsulfonyl)cyclopentadienyl] manganese tricarbonyl. The tube is heated at 400° C. for one hour after which time it is cooled and opened. The cloth has a uniform metallic grey appearance and exhibits a gain in weight of about 0.02 gram.

A further utility for our compounds is as drying agents in which case the compounds are incorporated in paints, varnish, printing inks, synthetic resins of the drying oil type, oil enamels and the like. A still further utility for our compounds is their use as chemical intermediates in the preparation of metal-containing polymeric materials or in the preparation of new organic materials.

Having fully defined the novel compounds of our invention, their mode of preparation and their many utilities, we desire to be limited only within the lawful scope of the appended claims.

We claim:

1. Compounds having the formula:

5

10

15

20

25

30

35

wherein R is a hydrocarbon group containing from one to about 8 carbon atoms, x is an integer ranging from 0 to 3, y is an integer ranging from 0 to 1 and M is an alkali metal.

2. Cyclopentadienyl carboxylic acid manganese tricarbonyl.

3. Compounds having the formula:

wherein R is a hydrocarbon group containing from about one to about 8 carbon atoms, x is an integer ranging from 0 to 3 and y is an integer ranging from 0 to 1.
